PORTABLE ACOUSTICAL HORN

Howard R. Berger, New York, N.Y., assignor to Transvox
Corporation, New York, N.Y.

Application November 13, 1956, Serial No. 43,723

Term of patent 14 years

(Cl. D26—14)

FIG. 2

FIG. 3

Fig. 1 is a perspective view of the Portable Acoustical Horn showing my new design as seen from the rear part thereof;

Fig. 2 is a front end view of the Portable Acoustical Horn as shown in Fig. 1; and

Fig. 3 is a rear end view of the Portable Acoustical Horn, as shown in Fig. 1.

I claim:

The ornamental design for a portable acoustical horn, substantially as shown.
